UNITED STATES PATENT OFFICE.

DAVID ZAVODNIK, OF NEW YORK, N. Y.

DRESS.

1,114,954.

Specification of Letters Patent.

Patented Oct. 27, 1914.

Application filed August 26, 1913. Serial No. 786,648.

To all whom it may concern:

Be it known that I, DAVID ZAVODNIK, a citizen of the United States, and a resident of the city of New York, borough of Brooklyn, in the county of Kings and State of New York, have invented a new and Improved Dress, of which the following is a full, clear, and exact description.

My invention relates to a new and improved form of lady's dress, particularly a house-dress, and an object of the invention is to provide a dress which will have a neat appearance about the waist, avoiding the objection raised to the loose fitting morning dresses, and which will adhere to the waist of the wearer irrespective as to whether or not corsets are worn.

A further object of my invention is to provide a dress, which may be readily donned, which can be adjusted to different sizes of waist, and which will have the appearance of a neatly fitting combined waist and skirt.

Another object of my invention is that it may be used as a maternity dress.

With the above and other objects in view, as will more fully hereinafter appear, the present invention consists in certain novel details of construction and arrangement of parts hereinafter fully described and particularly pointed out in the appended claims.

I attain the above outlined objects by making use of an outer belt adapted to encircle the waist of the wearer, the two ends of the said belt being attached to the dress, and a short band being stitched to the inside of the overlapping front portion of the dress. A series of clasps are attached to the inner band and a corresponding series of clasp-receiving members are attached to the ends of the outer belt at the end of the overlapped front portion, thus enabling the wearer to adjust same to different sizes around the waist.

Reference is to be had to the accompanying drawing forming a part of this specification, in which similar characters of reference indicate corresponding parts in all the figures, and in which—

Figure I is a perspective view showing a preferred embodiment of my invention on the wearer, a portion of the front being broken away to show the inner band; Fig. II is a perspective view showing my invention on the wearer, the front portion being

turned back to show the inner band; Fig. III is a transverse sectional view through the dress at the belt; and Fig. IV is a view showing the dress around the waist of the wearer and the outer belt held in place.

Described more in detail, my dress or garment comprises a waist portion 1 and a skirt 2, formed integral or stitched together. A belt 3 is stitched to the ends of the front portions as shown in Figs. II and III. A band 4 is stitched at the edges 13 and 14 to the inner side of the overlapping portion. A row of buttons or other suitable clasping members 7, 11, 9 and 5 are attached to the belt 3. A row of buttonholes or other clasp-receiving members 8, 10 and 12 are attached to the band 4. Each one of the clasp-receiving members 8, 10 and 12 are adapted to engage with either one of the clasps 7, 11 and 9. A clasp-receiving member or button-hole 6 is placed at the end of the belt 3 and is adapted to engage with either of the clasps or buttons 11, 9 or 5.

As shown in Fig. III, the clasp 7 is in position to engage with its receiving member 8 and the clasp 6 is in position to engage with its receiving member 5. In this position, the dress fits snugly around the waist of the wearer and the only button or clasp visible, is the button or clasp 6, as shown in Fig. IV. If desired, the button or clasp 6 may be under the belt 3 and in that event nothing is visible.

If it is desired to increase the waist dimensions of the dress, the clasp 10 is engaged with the receiving member 7, and the clasp 6 is engaged with the receiving member 9, which is placed in position to be opposite the clasp 6 in its new position. If it is desired to increase the waist dimensions of the dress still more, the clasp 12 is engaged with the receiving member 7 and the clasp 6 is engaged with the receiving member 11, which is so placed as to be opposite the new position of the clasp 6. If a still greater variation of waist dimension is desired, a few additional clasps similar to 8, 10 and 12 may be added, with corresponding members for the clasp 6, similar to the clasps 7, 11 and 9.

If it is desired not to have the clasp-receiving members 5 and 9 exposed when the dress is adjusted for the larger waist dimensions, the member 6, may be a hook instead of a clasp and the members 5, 9 and 11 may be eyes adapted to catch the hook 6. The

hook and eye will, of course, serve the same purpose viz. hold the end of the belt 3 in position.

It will be noted that by using the band 4 attached to the inner side of the overlapping portion, the main holding clasps are always invisible on the outside of the dress.

Having thus described my invention, I claim as new and desire to secure by Letters 10 Patent:

1. An open front dress, comprising a back and a pair of front portions, an inner band having its ends attached to the inside of one of the said front portions while the central portion of the band is free, a series of fastening means attached to the loose portion of the said inner band and a corresponding series of engaging fastening means attached to the outside of the second front portion, 15 the said sets of fastening means being arranged so that the overlap of one front portion over the other may be varied without exposing the said fastening means.

2. An open front dress, adapted to have its 20 front portions so that one overlaps the other,

an inner band having its ends attached to the inside of one of the said front portions while the central portion of the band is free, a series of fastening means attached to the loose portion of the said inner band and a corresponding series of engaging fastening means attached to the outside of the second front portion, an outer belt encircling the dress at the waist line and being attached at the ends of the two front portions, another 35 fastener attached to the inside of the overlapping front portion at its extreme end, the said fastening means being arranged so that the overlap of one front portion over the other may be varied without exposing the 40 said fastening means, while a corresponding fastener for the outer belt is found for every variation in the size of the waist.

In testimony whereof, I have signed my name to this specification in the presence of 45 two subscribing witnesses.

DAVID ZAVODNIK.
